STORM LANTERN BURNER

Brüno Nier, Beierfeld in Sachsen, Germany

Application July 14, 1936, Serial No. 90,572
In Germany August 12, 1935

6 Claims. (Cl. 67—53)

The present invention relates to storm lanterns and more specifically to improvements of the burner plate construction including the mounting thereof in lanterns of this general type.

5 In many storm lanterns heretofore known the burner or flame plate was secured to the wick tube and the wick tube together with the burner plate projected from the interior of the lower portion of the lamp. In such constructions the
10 wick tube together with the burner plate was often displaced out of its central position during the manufacture of the lamp or during use and thus the wick tube no longer retained its correct central position in the burner cap. Such dis-
15 placement of the flame plate caused the lantern to burn inefficiently.

An object of the present invention is to avoid such defects by enlarging the burner plate and constructing it in such manner that it is con-
20 stantly in contact with another part of the burner and thus permanently held in the correct position.

For this purpose the burner or flame plate is dished and preferably formed in the shape of a bowl. However, in other embodiments of the
25 invention it is sufficient for the flame plate to be constructed as a simple disc with or without an upturned edge. The lower part of the burner, the upper part of the burner or both parts can be
30 employed as a guide with which the burner or flame plate remains in contact in the finished lantern.

When the flame plate is in the form of a bowl and is held by the upper or lower part of the
35 burner, it need not be rigidly connected with the wick tube but an air gap can be provided between these two elements. Also, material which is a poor conductor of heat can be interposed between the flame plate and the wick tube as described
40 in my copending application Serial No. 90,573, filed July 14, 1936.

In addition, the flame plate can be provided with apertures which afford a materially improved supply of air to the flame which results
45 in a considerably improved burning of the flame.

The present invention not only ensures an absolutely reliable positioning of the wick tube and of the flame plate as already mentioned, but as the wick tube is reliably held in the central
50 position it is ensured that the lantern will burn well in all circumstances. The construction of the flame plate makes it possible to obtain a better supply of air to the flame. The resultant heat can be conducted away from the wick tube
55 in a reliable manner by way of the flame plate

to constructional elements of the lantern which are either not connected with the wick tube or have so slight a connection therewith that the transfer of the heat from them back to the wick tube does not take place. In this way, it is en-
5 sured that the storm lantern provided with the new burner burns well even in regions where the outer temperature is high. It must be em-
phasized that this advantage is obtained by simple means with the use of ordinary materials 10 and without appreciable increase in the cost of manufacture.

Certain embodiments of the invention are illus-
15 trated diagrammatically in the accompanying drawings, in which:

Fig. 1 shows one embodiment of the new burner in vertical section,

Fig. 2 is a section at right angles to Fig. 1.

Fig. 3 is a top plan view of the device shown in
Fig. 1.

Fig. 4 is a vertical section through a modified construction,

Fig. 5 is a section at right angles to Fig. 4.

Fig. 6 is a top plan view of the burner illus-
25 trated in Fig. 4.

Fig. 7 is a sectional view of another em-
bodiment of the invention,

Fig. 8 is a section at right angles to Fig. 7.

Fig. 9 is a plan top view of the burner shown
in Fig. 7.

Fig. 10 is a sectional view of a further embodi-
30 ment of the invention,

Fig. 11 is a section at right angles to Fig. 10
and

Fig. 12 is a sectional view along the line A—B 35
of Fig. 10.

The burner or flame plate as a whole is indi-
35 cated by *a* in the embodiment shown in Figs. 1 to
3 and it is in the form of an inverted bowl which
is secured to the wick tube *e* by flanges provided
40 on the latter. The connection however could be
effected in any other convenient manner. The
lower edge *b* of the burner plate *a* fits into the
base or lower part *c* of the burner in such a
45 manner that upper edge *d* embraces the lower
part of the flame plate. The portion *f* is so
shaped and dimensioned that it is embraced by
the burner cap *g* when the latter is slid over the
burner.

It is apparent that in this way the burner or
50 flame plate, the wick tube *e* and the wick itself
are secured centrally in a non-displaceable and
reliable manner.

In addition to the usual apertures *k* in the
burner plate, openings *h* and *i* are also provided
55

as shown in Fig. 3. These openings are of considerable importance for the proper burning of the lantern, because they improve the supply of air to the flame and thus assist materially in the proper burning of the lantern.

It is also clearly apparent that the heat generated is transferred with certainty from the wick tube *e* to the burner cap *g* and thus does not affect the flame detrimentally.

10 In the embodiment shown in Figs. 4 to 6 the inverted bowl-shaped burner or flame plate *a'* is separate from the wick tube *e'* and an air gap *l* is left between it and the wick tube. In this embodiment the burner plate surrounds the wick tube on all sides. The wick tube is reliably protected against displacement and the correct central position of the wick tube with respect to the burner cap is ensured.

15 The embodiment illustrated in Figs. 7 to 9 shows a burner or flame plate *a''* which is not connected with the lower part of the burner and has only a flange *m* which comes into contact with the inner wall of the burner cap *g*. The flame plate is thus held in the correct position by 20 the burner cap. The burner cap itself is always positioned centrally of the burner and the above described contact adequately ensures the central position of the wick tube even if there should be distortion during manufacture or during conveyance which may result in a displacement from the central position of the flame plate. The flange *m* also serves for the reliable transfer from the wick tube to the burner cap of the heat arising at the burner plate.

25 30 35 If the burner plate is rigidly connected with the wick tube, then the flange *m* can be dispensed with. In this case it is sufficient for the burner plate itself to be in contact with the burner cap as this adequately ensures the desired centering of the wick tube and the desired conveyance of heat away from the wick tube.

40 45 50 55 In the embodiment illustrated in Figs. 7 to 9 the apertures *k* shown in Fig. 3 are dispensed with. It has been found that the openings *h'* and *i'* are best adapted to supply the necessary air to the burning flame without material detriment to the behaviour of the lantern in spite of the effect of shaking and the effect of storms. Moreover, the omission of the apertures *k* enables the eddies otherwise occurring at these apertures when the lantern is exposed to shaking or to a storm to be avoided and this also constitutes a material improvement over storm lanterns of the prior art.

60 65 70 75 In the embodiment shown in Figs. 10 to 12 the inverted bowl-shaped burner plate *a''* is extended down to the wall of the oil reservoir *q*. The burner cap *g''* is carried on a shoulder of the burner plate *a''*. The slot *n* in the burner cap must be held in the correct position with reference to the aperture *o* of the wick tube and this is effected by interengaging notches *p¹* and *p²* as shown in Fig. 12 in the burner cap and burner plate. In this case the lower part *n'* of the burner plate constitutes the lower part of the burner cap.

75 This construction of the burner plate affords the advantage that the heat which is produced at the burner plate is conveyed directly to the oil reservoir, i. e. is transferred to the component parts of considerable surface area and the heat thus is dissipated in the best possible manner.

It will be apparent, therefore, that the dimensioning and shaping of the burner plate in accordance with the invention ensures the requisite

central position of wick tube and burner in a simple manner and improves the operation of the storm lantern while the provision of the large openings in the burner plate and the elimination of the numerous apertures otherwise employed 5 gives a very favorable supply of air to the flame.

I claim:

1. A burner for a storm lantern comprising, a wick tube extending upwardly from the central portion of the burner, an inverted bowl-shaped flame plate having the inverted base thereof surrounding the upper end of the wick tube and a continuous downwardly extending skirt of a relatively large surface area, a burner cap positioned 10 over the wick tube to provide a cover for said flame plate, said cap having a downwardly extending portion embracing the skirt of said flame plate whereby a relatively large surface contact is provided between the flame plate and the burner 15 cap for conducting heat from the plate to the cap.

2. A burner for a storm lantern comprising, a wick tube extending upwardly from the central portion of the burner, an inverted bowl-shaped flame plate having the inverted base thereof supported by the upper end of the wick tube and a solid downwardly extending skirt of a relatively large surface area, a burner cap positioned over the wick tube to provide a cover for said flame plate, said cap having a downwardly extending 20 portion embracing the skirt of said flame plate whereby a relatively large surface contact is provided between the flame plate and the burner cap for conducting heat from the plate to the cap.

3. A burner for a storm lantern comprising, a wick tube extending upwardly from the central portion of the burner, an inverted bowl-shaped flame plate having the inverted base thereof supported by the upper end of the wick tube, a lower burner portion, said flame plate having a 25 continuous downwardly extending portion of a relatively large surface area, said downwardly hanging skirt being adapted to rest on said lower burner portion, a burner cap positioned over the wick tube to provide a cover for said flame plate, 30 said cap having a downwardly extending portion embracing the skirt of said flame plate whereby a relatively large surface contact is provided between said flame plate and the burner cap including a relatively large contact between the 35 flame plate and the lower burner portion for conducting heat from the plate to the cap and the lower burner portion.

4. A burner for a storm lantern comprising, a wick tube which extends upwardly from the central portion of the burner, a lower burner portion, an inverted bowl-shaped flame plate having the inverted base thereof supported by the upper end of the wick tube and having a solid downwardly extending skirt of relatively large area 40 which extends into and is embraced by said lower burner portion, a burner cap positioned over the wick tube to provide a cover for said flame plate, said cap having a downwardly extending portion embracing the skirt of said flame plate whereby a 45 relatively large surface contact is provided between the flame plate and the burner including a contact between the flame plate and the lower burner portion for conducting heat from the plate to the cap and the lower burner portion.

5. A burner for a storm lantern comprising, a fuel reservoir, a wick tube extending upwardly from the fuel reservoir centrally of the burner, an inverted bowl-shaped flame plate having the inverted base thereof supported at the upper end 50

of said wick tube and a downwardly extending skirt of a relatively large surface area the lower end of which is adapted to embrace and rest on said fuel reservoir, a burner cap positioned over 5 the wick tube to provide a cover for said flame plate, said cap having a downwardly extending portion embracing the skirt of said flame plate whereby a relatively large surface contact is established between the flame plate and the 10 burner cap including a relatively large surface contact between the lower end of the flame plate and the reservoir for conducting heat from the plate to the cap and the reservoir.

6. A burner for a storm lantern comprising, a 15 wick tube extending upwardly from the central

portion of the burner, an inverted bowl-shaped flame plate having the inverted base thereof surrounding the upper end of the wick tube and a downwardly extending skirt of a relatively large surface area and having a notch in said surface, a 5 burner cap positioned over the wick tube to provide a cover for said flame plate, said cap having a rib in a downwardly extending portion thereof, said rib fitting into said notch and the downwardly extending portion of said cap embracing 10 the skirt of said flame plate whereby the cap is maintained in a fixed position with respect to said flame plate.
